Primary Examiner — Susan Bennett Hattan*Assistant Examiner* — Marie Fast Horse(74) *Attorney, Agent, or Firm* — TraskBritt, P.C.(57) **CLAIM**

The ornamental design for a microphone suspension mount, as shown.

DESCRIPTION

FIG. 1 is a bottom view of a microphone mount assembly, showing our new design;

FIG. 2 is a front view of the design;

FIG. 3 is a isometric view of the design;

FIG. 4 is a isometric view of the design;

FIG. 5 is a rear view of the design;

FIG. 6 is a side view of the design; and,

FIG. 7 is a top view of the design.
